CLAIM

The ornamental design for a hat as shown and described.

DESCRIPTION

FIG. 1 is a front perspective view of a hat showing my new design;

FIG. 2 is a top plan view thereof;

FIG. 3 is a bottom plan view thereof; and,

FIG. 4 is a perspective view with a portion of the tassels parted.

The broken line showing of the person in FIG. 1 is for illustrative purposes only and forms no part of the claimed design.

FIG. 1

FIG. 2

FIG. 3

FIG. 4
